Primary Examiner — Cynthia M Chin(74) *Attorney, Agent, or Firm* — Foley & Lardner LLP(57) **CLAIM**

I claim the ornamental design for a handle, as shown and described.

DESCRIPTION

FIG. 1 is a perspective view of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The ornamental design which is claimed is shown in solid lines in the drawings. The dash-dot boundary lines define a boundary of a claimed design and form no part of a claimed design. The broken lines in the drawings are for illustrative purposes only and form no part of the claimed design.
